PLIED YARN AND PLIED YARN FABRIC AND
METHOD OF MAKING SAMEHoward Byers Jackson, Kings Mountain, N. C.,
assignor to Neisler Mills, Inc., Kings Mountain,
N. C., a corporation

Application April 13, 1948, Serial No. 20,624

6 Claims. (Cl. 28—76)

1

This invention relates to plied textile yarns and fabrics made therefrom.

In accordance with the present invention the plied yarn is of such character that the yarn of one of the plies projects from the yarn of another ply along the length of the latter whereby fabric woven from such yarn has certain desirable characteristics or properties. More particularly such fabric has a full lofty hand, appears thick in comparison with its weight, and has a somewhat metallic appearance.

The plied yarn of the present invention is produced by plying direct spun synthetic yarn, which is shrinkable by wetting, with yarn which is less shrinkable by wetting than said direct spun yarn. The less shrinkable yarn may be of either natural or synthetic origin and may be continuous filament yarn or spun yarn which is less shrinkable than direct spun rayon or nylon yarn. As a result of the differential wet-shrinkability of the yarns of which the plied yarn is produced, in accordance with the present invention, wetting of the plied yarn, either as yarn, before being incorporated in the fabric, or after it is incorporated in the fabric, results in the direct spun yarn of the plied yarn shrinking considerably more than the other yarn of the ply, whereby the latter projects or fluffs up laterally of the plied yarn. As a result, the fabric formed from said yarn has the characteristics referred to above.

The invention will now be described in greater detail with reference to the accompanying drawings which however are to be considered as illustrative of the invention but not in limitation thereof.

In the drawings:

Fig. 1 is a plan view, on an enlarged scale, of a piece of fabric embodying the present invention;

Fig. 2 is a view, on a greatly enlarged scale, of a length of plied yarn of the present invention, before said yarn is treated for shrinking the same;

Fig. 3 is a view similar to Fig. 2 showing the plied yarn after it is subjected to the shrinking operation.

As shown in Fig. 2, the plied yarn 10 comprises direct spun synthetic yarn 12 and yarn 14 which is less shrinkable than said direct spun yarn 12. The direct spun yarn 12 may be produced from filamentary rayon, including nylon, according to any suitable direct spinning process, for example as described in the application of Charles E. Neisler, Jr., Serial No. 640,727, filed January 12, 1946, and now abandoned. As described in said application, direct spun yarn is produced from

2

continuous rayon filaments by tensioning and rupturing said filaments to produce staple fibers which are spun into yarn. As a result of the tensioning of the filaments, the staple fibers of the spun yarn are in attenuated condition and will shrink considerably when wetted without requiring stretching of the spun yarn. It will be understood that the wetting of the direct spun yarn may be accomplished either by the dyeing operation or by a separate operation, the former being preferred. As stated above the less shrinkable yarn 14 may be either natural or synthetic yarn and if desired may be either continuous filamentary yarn or spun yarn. Said less shrinkable yarn 14 may also be constituted of direct spun yarn which has been shrunk before it is plied with the companion non-shrunk yarn 12. As shown in Fig. 2 the less shrinkable yarn is twisted around the core of the direct spun yarn 12, the latter being the core of the plied yarn thus formed.

The plied yarn 10 may now be used to produce the fabric which when wetted, for example in the dyeing operation, will cause the direct spun yarn 12 to shrink thereby causing the less shrinkable yarn 14 of the plied yarn to project or fluff laterally of the companion direct spun yarn 12 along the length of the plied yarn, as illustrated more or less diagrammatically in Fig. 3 which is to be considered in comparison with Fig. 2. The fluffed yarn thus produced by the shrinking operation is indicated at 10A in Fig. 3 and is also indicated by the same reference character in the fabric F shown more or less schematically in Fig. 1.

In the fabric F the plied yarn 10A is shown as the warp threads of the fabric, the weft threads being indicated at 16, but this may be reversed. Preferably the threads 16 are much thinner than the threads formed of the plied yarn 10A and the weave of the fabric is preferably such that the face of the fabric is constituted mainly by the threads formed of the plied yarn 10A, while the back of the fabric is constituted mainly by the thinner threads 16. It will be understood that this result may be readily accomplished by floating the threads 16 over a considerable number of the plied yarn threads 10A at the back of the fabric. It will be understood however that I do not limit myself to any particular weave of fabric, and further it will be understood that the fabric may be formed so that only sections thereof are composed of threads formed of the plied yarn 10A. In this connection it will be understood that various pattern effects may be produced according to the sections of the fabric which are formed of threads of the plied yarn in

contrast with sections of fabric which are formed of yarn of different character. Fabrics produced in accordance with the present invention may be made of yarn of various sizes according to the intended uses of the fabrics. More particularly, the fabrics may be used for furniture, dresses and other garments, etc.

As illustrated in Figs. 2 and 3 the yarn 14 is preferably thicker, i. e., of a larger size than the direct spun yarn 12 of the plied yarn. It will be understood however that the two plies of the plied yarn may be of the same thickness or size or may otherwise vary in this respect relatively to each other depending upon the desired effect. It is also preferred that the less shrinkable yarn 14 of the plied yarn 10 have less twist than the more shrinkable yarn 12. In accordance with the presently preferred mode of practicing the present invention, the direction of twist of yarn 12 is opposite that of yarn 14, and in the plying operation the plying twist is in such direction as to increase the twist of the direct spun yarn 12 and to decrease the twist of the yarn 14.

It will be understood that while I have illustrated and described the presently preferred form of my invention, the latter is susceptible to various changes and modes of practicing the same. Accordingly it will be understood that various changes may be made without departing from the underlying idea or principles of this invention within the scope of the appended claims.

Having thus described my invention, what I claim and desire to secure by Letters Patent, is:

1. A composite yarn comprising a direct spun synthetic yarn which is attenuated by the direct-spinning thereof and is shrinkable when wetted and a second yarn which is less shrinkable by wetting than said first mentioned yarn plied with the latter in said attenuated shrinkable condition thereof whereby when the resulting composite yarn is wetted said first mentioned yarn shrinks more than said second yarn and the latter has portions which project laterally of said direct spun yarn in said composite yarn.

2. Plied yarn comprising a direct spun synthetic yarn plied with a companion yarn which is less shrinkable by wetting than said direct spun yarn whereby shrinkage of the plied yarn by the wetting thereof causes said companion yarn to project laterally of said direct spun yarn along the length thereof so as to produce a fluffed plied yarn.

3. A composite yarn comprising a direct spun synthetic yarn which is attenuated by the direct-spinning thereof and is shrinkable when wetted and a second yarn which is thicker and has less

twist than said direct spun yarn, said second yarn being less shrinkable by wetting than said direct spun yarn and plied with the latter in said attenuated shrinkable condition thereof whereby when the resulting composite yarn is wetted said first mentioned yarn shrinks more than said second yarn and the latter has portions which project laterally of said direct spun yarn in said composite yarn.

4. A woven fabric comprising threads formed of a direct spun synthetic yarn which is attenuated by the direct-spinning thereof and is shrinkable when wetted and a second yarn which is less shrinkable by wetting than said first mentioned yarn plied with the latter in said attenuated shrinkable condition thereof whereby when the resulting threads are wetted said first mentioned yarn shrinks more than said second yarn and the latter has portions which project laterally of said direct spun yarn in said fabric.

5. The method of making a fluffed yarn, comprising the steps of plying a direct spun shrinkable synthetic yarn which is attenuated by the direct-spinning thereof with a less shrinkable yarn, and thereafter wetting the plied yarn to shrink said direct spun yarn and thereby cause said less shrinkable yarn to project laterally of said direct spun yarn along the length thereof to result in a fluffed yarn.

6. The method of making a fluffed fabric, comprising the steps of weaving the same from threads including threads formed of plied yarn comprising a direct spun shrinkable synthetic yarn which is attenuated by the direct-spinning thereof plied with a less shrinkable yarn, and wetting the woven fabric to shrink said direct spun yarn and thereby cause said less shrinkable yarn to project laterally of said direct spun yarn along the length thereof to result in a fluffed fabric.

HOWARD BYERS JACKSON.
